UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

AUTOMATIC TELEPHONE EXCHANGE.

Substitute for application Serial No. 191,542, filed September 15, 1917. This application filed June 20, 1919, Serial No. 895,540. Renewed January 26, 1922. Serial No. 532,038.

To all whom it may concern:

Be it known that I, FRANK A. LUNDQUIST, a citizen of the United States of America, and a resident of the city of Chicago, county of Cook, and State of Illinois, have invented certain new and useful Improvements in Automatic Telephone Exchanges, of which the following is a specification.

10 My invention relates to automatic telephone exchanges, and has for its object an improved arrangement of trunk connections which will bring about a reduction in the number of such trunks and the amount of 15 apparatus required to equip an exchange.

This application is a substitute for my former application, Serial No. 191,542, filed Sept. 15, 1917.

In ordinary exchanges, a trunk selecting switch has its wipers normally located near, or moved to, a group of contact terminals. In selecting a trunk, these wipers are automatically advanced over the terminals of this group until they reach terminals which 25 represent an idle trunk. When this point is reached the switch is automatically stopped with its wipers in engagement with the found trunk, which trunk is automatically made "busy" so that it will not be conflictingly selected by some other switch moving its wipers over other terminals of the same trunk.

The trunk thus automatically selected leads to another switch which, in turn, selects an idle trunk leading to still another switch. The number of such automatic selections in making a call is determined by the size of the exchange, the last automatic 35 selection being of a trunk leading to a connector switch. The connector switch has its movements controlled by the subscriber making the call, and connects to terminals of lines leading to the local stations of subscribers.

40 The first trunk-selecting switches in an exchange are usually called "line switches" and are connected to the lines leading to the local stations. There is thus one line switch for each subscriber. The line switches usually have terminals for from ten to twenty trunks leading to selectors, which are the switches between the line switches and the connectors. The selectors usually have ter-

minals for one hundred trunks, arranged in ten groups of ten trunks in each group. The 55 subscriber selects the desired group, but the selector automatically selects an idle trunk out of the previously selected group.

The line switches and the selectors of the present exchange are assumed to be the same 60 as those in ordinary use, or to be any switches which will accomplish the same result. The connectors, however, are assumed to have terminals for one thousand lines leading to local stations. I have described such a 65 switch in my pending application Serial Number 186,448, filed August 16, 1917, issued as Patent No. 1,475,497, Nov. 27, 1923. The actual construction of none of these switches is, however, material to the present 70 application, as this application relates solely to the trunking and grouping organization used.

The switches in an organization are arranged in groups, and the number of trunks 75 leading to the switches of a particular group is determined by the size of the group and the traffic conditions. When the groups consist of one hundred switches each, normal traffic conditions require about fourteen 80 trunks to serve them. It is known, however, that by making the groups larger, a less percentage of trunks is necessary to serve them. Thus, in groups of one thousand, fifty trunks, or five per cent of trunking, is 85 sufficient. The object here is to obtain the advantage of large groups without making large and cumbersome switches. In other words, to obtain large groups while using standard switches now employed in small 90 groups of one hundred or less.

The accompanying drawing represents, on three sheets, a part of an organization serving one hundred thousand subscribers. The sheets are extensions of each other, Sheet 95 No. 1 being at the left, Sheet No. 2 next, and Sheet No. 3 at the right. The three sheets together represent the first one thousand line switches, and eight hundred out of the second one thousand. The line switches are 100 represented at A in a row at the bottom of the three sheets. The first selectors are represented at B in the next row above the line switches. Similarly, the second selectors are represented at C, and the connectors at D. In this organization the one 105

hundred thousand capacity is reached without the use of third selectors.

Each switch is represented by a single contact maker, or wiper, 10, 11, 12, 13, or arbitrarily by the circles in a line with the lower ends of the wipers. A cable 14 having wires for one thousand lines extends along below the line switch A, which wires terminate each in a different wiper 10. Four wipers 10 are arbitrarily used to represent a sub-group of one hundred line switches, and the cable 14 does not extend beyond ten such sub-groups. Another cable 15 serves in the same way the line switches of the second group, eight sub-groups of which are shown. In the same way other cables would serve other groups of line switches.

Each wiper 10 is movable, for automatic trunk selecting purposes, over a series of contacts terminals, one set of which is arbitrarily represented at 16 over the left hand wiper 10 on Sheet No. 1. From the bank wires, represented as running thru these contacts 16, are taps leading to the wipers 11 representing first selectors. Adjacent to each wiper 11 are ten rows of contact points, each row having ten points therein. This ten by ten is arbitrarily represented as three by three at 17, three being considered as representing ten.

The bank wires (trunks) running thru contacts 16 extend different distances, but all are limited to the first one thousand line switches. Those belonging to the second one thousand are multiplied to other contact points, one set of which is represented at 18 on Sheet 2. In the same way each thousand line switches has bank wires limited to itself.

Referring to the lower left hand part of Sheet No. 1, it will be seen that the two lower trunks 19 extend over and are limited to the first one hundred line switches in the first group of one thousand. Similarly, the second one hundred line switches have two trunks 19^a which are limited to this second one hundred. The third one hundred has two trunks 19^b, the fourth has two trunks 19^c, and so on.

Next above the trunks 19 are two other trunks 20 which extend over and are common for two hundred line switches, but are limited to this two hundred. The next two hundred have the common trunks 20^a, and so on. Next above the trunks 20 are five trunks 21 which extend over and are common for five hundred line switches. The second five hundred line switches in the first one thousand have similar trunks 21^a. Next above the trunks 21 are ten trunks 22 which extend over the entire one thousand line switches, and are common for the use of the entire number. Each one thousand line switches in the entire exchange has its trunks arranged in the same way.

Assuming that the first line switch repre-

sented at the lower left hand corner of Sheet No. 1 is started into operation, it will first engage terminals of trunks which do not extend beyond the sub-group of one hundred line switches to which it belongs. If both of those are busy at the time, it will pass on to the terminals of trunks common to two hundred line switches. If those are busy, it will pass on to trunks common to five hundred line switches. If those also are busy, it will pass on to trunks common to the entire thousand.

It will be seen from the foregoing that there are fifty trunks serving the first one thousand line switches, yet no line switch finds it necessary to traverse more than nineteen terminals to have the full benefit of the five per cent trunking. The principle here involved makes a small number of trunks (preferably two or three) common for a sub-group, another small number common for two or more sub-groups, another number common for a greater number of sub-groups, and still another number (preferably large) common for the entire group. The numbers given (two, two, five, and ten, yielding a total of nineteen) are convenient, but it will be obvious that there may be a variation of the number of trunks in each stage, and even a variation in the number of stages, without departing from the principles involved. Either of these variations may vary the total number of trunks without change of principle.

As far as making the final connection to a wanted subscriber, it does not make any difference which one of these nineteen trunks the line switch finds idle. For example, it will be assumed that the subscriber whose line switch is represented at the lower left hand corner of Sheet No. 1 wants to make connection to some other subscriber in the same thousand. If he finds either of the trunks 19 idle he gets one of the two selectors 11 at the extreme left as is indicated by the tap wires leading from the trunks 19. Wanting a subscriber in the first ten thousand, the calling subscriber starts his switch 11 moving along the first row of contact points which connects him to an idle trunk in cable 23 and gives him an idle switch 12 in the group of ten at the extreme left. As the bank contacts of these switches are multiplied together in the ordinary manner, it does not make any difference which one he gets. Having thus got possession of a switch 12, and wanting some connection in the first thousand, he starts his switch wipers up the first row of contacts and secures some idle trunk in the cable 24. This gives him an idle connector 13 in the group of ten at the extreme left. If the wanted subscriber is in the first hundred, the connector 13 is advanced along the first row of contacts to the correct number. If the want-

ed subscriber is in the second hundred, the connector is moved laterally to the second row, and then advanced. And so on.

If the line switch, instead of connecting 5 to a trunk 19 as just described, should not find an idle trunk until it reached the last one of the trunks 22 it would come to switch 25 shown near the middle of Sheet No. 2. This switch, like all of those in its immediate neighborhood, would have its contacts multiplied to the same bank wires as those shown for the adjacent wiper 11. Moving 10 up the first row of contacts (as in case previously described) the selector would find 15 an idle trunk in cable 26 leading to one of the second selectors C in the fifth sub-group of such selectors shown in the middle of Sheet No. 2. Again moving up the first row of contacts the second selector would 20 find an idle trunk in cable 27 leading to a connector D in the fifth sub-group. All of the connectors in the five sub-groups have their contact points multiplied to the wires in cable 14, and hence the connection to the 25 desired subscriber would be the same as that before described.

It will be observed that the drawings show fifty connectors, all of which have their contacts multiplied to the wires in 30 cable 14 leading to the one thousand subscribers represented by their wipers 10 in the first main group. Hence, any one of the fifty connectors may be used to complete the connection to a called subscriber. 35 Also it is to be observed that between the line switches and the connectors there are fifty first selectors and fifty second selectors, any one of which may be used in completing 40 connections. In the manner just described, the trunking connections may be traced on the drawing from any line switch in the first thousand to any other line switch in the same thousand. Hence the drawings illustrate five per cent trunking in groups of 45 one thousand without large or unusual switches at any point except the connectors. It will be obvious that by inserting third 50 selectors the same plan can be carried out with ordinary connectors without other change.

The cable 24 (leading to the first sub-group of connectors in the first thousand) extends thru the exchange and may be traced on Sheets Nos. 2 and 3. Hence, this 55 cable may be reached by connections from the line switches in any other thousand. Thus, if the first line switch in the second thousand (shown adjacent to the vertical part of cable 15 on Sheet No. 2) should get 60 the first selector directly over it and this first selector should advance on the first row, it would come to cable 28, and thence thru a second selector to cable 24. Similarly, 65 cable 27, and other intermediate cables, extend thru the exchange and may be reached,

thru first and second selectors, by any line switch in any thousand.

If the subscriber having the first selector in the first thousand wanted to call some person in the second thousand, he would 70 proceed as before up to the second selector 12. Then, instead of advancing up the first row of contacts he would shift his wiper to the second row and then advance up that row. This would make connection to an 75 idle trunk in cable 29, which extends into the second thousand and has a branch 30 leading to the connectors shown in the upper right hand corner of Sheet No. 2. If the person wanted is in the third thousand, then the second selector 12 would be shifted 80 to and advanced on the third row of contacts. This would give a trunk in cable 31 leading to connectors in the third group of one thousand. In the same way shifting 85 the second selector to the third, fourth, fifth or later row of contacts would carry the connections to the third, fourth, fifth or later thousand in the first ten thousand.

If the subscriber to be called is in the 90 second ten thousand, then, in making a call, the first selector 11 is shifted to the second row and secures an idle trunk in the cable 32. This cable is united with other cables to form a large cable 33 extending to the 95 eleventh thousand, twenty-first thousand, thirty-first thousand, etc. The particular cable 32 would have taps emerging from cable 33 at the eleventh thousand and would give a second selector in the same 100 way that a second selector was secured from cable 23 in the previous description. Having found a second selector in the second ten thousand, this selector can be advanced 105 on any row of contacts to get a connector in any thousand, in the same manner as described for the first ten thousand. If the subscriber to be called is in the third ten thousand, then the calling subscriber moves his first selector to the third row and gets 110 a trunk in cable 34 which unites with cable 33 and later emerges at the twenty-first thousand. And so on.

The switches and trunks shown on Sheets 115 Nos. 2 and 3 belong in the second one thousand and correspond exactly to those described as being in the first one thousand. The cables reached by the first selectors are gathered in the same way into a large cable like 33, and later emerge at the twelfth, the 120 twenty-second, and thirty-second, etc., thousand. The same arrangement carried out in the same way extends to the other parts of the exchange.

In ordinary exchanges using groups of 125 one hundred subscribers, ten per cent of trunking meets the ordinary runs of calls. The reason why approximately fourteen per cent of trunking is necessary in such exchanges is that occasionally there is a con- 130

gestion of calls from some particular hundred, and unless there is provision for meeting such a congestion the system breaks down as far as meeting demands is concerned. The smaller the group the greater is the liability of such congestion, and the larger the group the less there is of such liability.

In my arrangement I divide subscribers 10 into groups of one thousand and then divide these into sub-groups of one hundred. For these sub-groups I have shown a possible nineteen per cent of trunking for each hundred, tho I might make it fourteen or 15 any other percentage required. The percentage for the thousand is, however, only five per cent. That is ordinarily sufficient to meet any kind of congestion, because congestions of traffic are usually local.

20 Passing beyond the line switches it will be seen that I have arranged the selectors over each other in sub-groups of ten. When any first selector is being moved to secure a called subscriber in the first ten thousand 25 it moves up the first row of contacts which gives it connection to one of ten second selectors. Going to the second row would carry the connections off into the second ten thousand. A first selector is able to seize 30 only one of the ten trunks leading to a corresponding sub-group of second selectors, and similarly, an advancing second selector is able to seize only one of the ten trunks leading to connectors.

35 To casual inspection it might seem that this provided five per cent trunking in small groups, and that a congestion of calls might center on the first and second selectors. Such, however, is not the fact as can be made 40 evident by returning to the trunking arrangement from the line switches to the first selectors.

The first selectors of the first thousand are arranged in ten groups of five in each group, 45 the entire fifty serving one thousand subscribers. Each line switch has access to nineteen of the fifty first selectors, but this access is distributed thru different parts of the fifty, and not concentrated at one place.

50 The first one hundred line switches have access to eight first selectors out of the first group of ten; to four of the second group; and to two of the fifth group. The other line switches of each hundred have their 55 trunk connections similarly distributed over the different groups of first selectors. Consequently it will be seen that a congestion of calls originating in any hundred line switches has those calls distributed to different groups of selectors and not concentrated in any one group. And a distribution which reaches the first selectors is continued in the same way to the second selectors and to the connectors.

60 If it is desired to increase the selectors

from five per cent to six per cent it may be done by adding a third bank wire 19, 19^a, 19^b, etc., for each hundred line switches, and inserting an extra selector for each such bank wire. This would give twenty contact 70 points for each line switch to run over. Or the same increase to six per cent may be obtained by inserting two extra bank wires 20, 20^a, etc., with selectors, for each two hundred line switches. This would give 75 twenty-one contact points for each line switch to run over. Also, the same result would be obtained by inserting five extra bank wires 21 and 21^a, or by inserting ten extra bank wires 22. By any one of these 80 additions the percentage of trunking may be further raised to seven per cent for extremely busy sections.

In exchanges in which the traffic is light it may be that four per cent of trunking in 85 groups of one thousand will care for every contingency. In such cases the desired reduction may be obtained by the reverse process to that just described. Thus, omitting one of the wires 19, 19^a, etc., will leave 90 only forty selectors to one thousand trunks. Similarly, omitting the two trunks 20, 20^a, etc., or the five trunks 21 and 21^a, will each 95 accomplish the same result. Either of these last two, however, will cut out one of the stages by which congested calls are distributed thru different parts of the apparatus.

From the foregoing description it will be 100 seen that I have set forth a system of distributing congested calls thru different parts of the exchange so that the percentage of trunking may be largely reduced from what is now necessary to meet the requirements 105 of a given traffic. Also, that I accomplish these results by the use of the same apparatus now commonly employed. Also, that the system described is extremely flexible and may be adapted to widely varying conditions.

110 What I claim is:

1. In an automatic telephone exchange, a series of line switches divided into groups, a series of selectors divided into corresponding groups, and a series of trunk connections between the line switches and the selectors, said trunk connections being divided into classes which do not correspond to said groups but which permit any line switch to automatically complete direct connections 115 to some idle selector in any group of selectors.

2. In an automatic telephone exchange, a series of line switches each having contact terminals thereon, a series of selectors more numerous than the terminals on any line switch, said selectors being divided into groups less numerous than the terminals on a line switch, and trunks connecting each selector to terminals on a plurality of 120 125 130

line switches, said trunks being divided into classes which differ from the groups and are determined by the number of line switches to whose terminals they are multipled.

3. In an automatic telephone exchange, a series of line switches divided into groups, a series of selectors also divided into groups, and trunk connections extending from the 10 selectors to contact terminals on the line switches, said trunk connections being divided into classes part of which classes connect a plurality of groups of selectors to a plurality of groups of line switches.

15 4. In an automatic telephone exchange, a series of line switches each having a plurality of contact terminals, a series of selectors more numerous than the contact terminals on a line switch and divided into 20 groups less numerous than such terminals, means by which upon operating a line switch it will automatically select both group and selector so as to complete connections to an idle selector in some group having such idle 25 selector, and other electrical connections by which final telephonic connection reaches the same place without respect to which group is thus automatically selected.

5. In automatic telephone exchanges, the 30 combination with line switches divided into groups, and a lesser number of selectors divided into corresponding groups, of direct trunk connections between line switches and selectors, said connections being so arranged 35 that calls coming thru line switches will be sent normally to the selectors of corresponding groups, but upon a congestion of calls coming thru any particular group of line switches the surplus of such calls will 40 be distributed to selectors of other groups over said connections.

6. The combination with line switches divided into groups, and a lesser number of selectors divided into corresponding 45 groups, of trunk connections from line switches to selectors so arranged that upon a congestion of calls coming thru any group of line switches all calls beyond a certain number will be distributed to different 50 groups of selectors, and means by which a call finally reaches the same place without respect to what group of selectors it passes thru.

7. In a telephone system, a series of subscribers' individual line switches divided into groups, a series of selectors divided into corresponding groups, a series of trunk con-

nections between said individual switches and said selectors, said trunk connections being divided into classes which do not 60 correspond to said groups but which permit any individual switch to automatically complete connection to some idle selector in any group of selectors.

8. In a telephone system, line switches divided into groups, selectors divided into corresponding number of groups, trunk lines accessible to said line switches terminating in said selectors and divided into first, second and third choice groups which 70 do not correspond to said line switch or selector groups, each first choice trunk line individual to a group of line switches and to a group of selectors, each second choice trunk line common to two groups of line 75 switches and individual to one group of selectors, each third choice trunk line being common to a plurality of line switch groups and individual to one group of selectors, and said trunk lines permitting any line 80 switch to connect with a selector in any group of selectors.

9. In a telephone system, line switches divided into groups, selector switches divided into corresponding number of groups, 85 first choice trunk lines accessible to only one group of line switches and terminating in selector switches of only one group, second choice trunk lines accessible to two groups of line switches and terminating in selector switches of only one group, third choice trunk lines accessible to a plurality of groups of line switches and terminating in a plurality of groups of selector switches, and said trunk lines permitting any line 90 switch to connect with a selector switch in any group of selector switches.

10. In a telephone system, a series of subscribers' individual line switches divided into groups, a series of selectors divided into corresponding number of groups, trunk lines connecting said line switches and said 100 selectors, certain of said selectors being accessible to only one of said line switch groups, other of said selectors accessible to only two of said line switch groups, still other of said selectors being accessible to all of said line switch groups, and the trunk connections between said last mentioned 105 selectors and line switches arranged so that any line switch in any group of line switches 110 can select an idle selector in any group of selectors.

FRANK A. LUNDQUIST.
